DISPENSING DEVICE

Arthur Taube, Jr., Floral Park, N. Y.

Application October 8, 1940, Serial No. 360,213

9 Claims. (Cl. 221—102)

This invention relates to new and useful improvements in a self-feeding shaving brush.

More specifically the invention comprises the construction of a self-feeding shaving brush characterized by a shaving brush having a handle with a chamber at one end thereof for liquid shaving soap, bristles at the other end thereof, and a means for conveying the shaving soap from the chamber to said bristles in a manner to permit lather to be formed when desired.

Still further the invention proposes to characterize the means for conveying the shaving soap by a passage provided with a depressible plunger arranged in a manner to force the shaving soap from the chamber to the bristles when properly operated.

A further object of this invention proposes the provision of a means for fixedly closing the passage in a manner to prevent the shaving soap from being forced from the chamber when the shaving brush is shaken for removing excess water therefrom.

A further object of this invention is the construction of a self-feeding shaving brush as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a self-feeding shaving brush constructed in accordance with this invention.

Fig. 2 is a vertical sectional view of Fig. 1.

Fig. 3 is an enlarged vertical sectional view taken on the line 3—3 of Fig. 2.

Fig. 4 is an enlarged vertical sectional view taken on the line 4—4 of Fig. 2.

Fig. 5 is a perspective view of the disc used for supporting the bottom end of the spring of 45 the blow off valve.

Fig. 6 is a vertical sectional view of Fig. 5.

The self-feeding shaving brush, according to this invention, includes a brush body 10 provided with bristles 11 at one end and a chamber 12 at the other end. The chamber 12 is hollowed out of the end of the brush body 10 and is closed by means of a cover 13. Threads are arranged between the adjacent portions of the cover 13 and the brush body 10 for maintaining the cover 55

13 in position across the open end of the chamber 12.

A means is provided for connecting the interior of the chamber 12 with the bristles 11 for the purpose of conveying the shaving soap contained within the chamber to the bristles. This means is characterized by a passage 14 consisting of a top offset end portion 14^a which continues into a main central portion 14^b. The main central portion 14^b extends laterally entirely through the brush body 10. The passage 14 further continues into a bottom concentric portion 14^c. A plunger 15 is slidably mounted within the main central portion 14^b of the passage 14 and has one end projected therefrom. The inner end of the plunger 15 is provided with a forwardly projecting tail portion 15^a which is adapted to extend across the bottom end of the top offset end portion 14^a of the passage 14 for closing the same and preventing shaving soap from entering the main central portion 14^b when the plunger 15 is urged inwards. A spring 16 is located within the main central portion 14^b of the passage 14 and acts between the inner end of the plunger 15 and a plug 17 used for sealing the open end of the main central portion. The spring 16 acts to urge the plunger 15 into its extended position in which the forwardly projecting tail portion 15^a thereof will not be projected across the bottom end of the top offset end portion 14^a of the passage 14.

A means is provided for preventing the spring 16 from shooting the plunger 15 out of the end of the main central portion 14^b and for preventing plunger from turning with relation thereto.

This means comprises a downwardly extended key 18 formed on the brush body 10 and which engages a longitudinal groove 19 formed in the plunger 15. The key 18 permits the plunger 15 to be freely urged inwards against the holding action of the spring 16. However, it acts to prevent the spring from urging the plunger 15 into a disengaged position with relation to the main central portion 14^b of the passage 14. The construction is such that when the plunger 15 is urged inwards it will immediately close the bottom end of the top offset end portion 14^a of the offset and force the soap contained within the main central portion 14^b into the bottom portion 14^c of the passage to pass to the bristles 11.

A spring controlled blow off valve is located within the bottom portion 14^c of the passage and is arranged to permit the soap to pass therethrough when the plunger is urged inwards but to prevent the soap from being sucked back into the main central portion 14^b of the passage 14.

when plunger is again moved outwards by the expansion of the spring 16. This blow off valve is characterized by a ball 20 located within the top end of the bottom portion 14^c of the passage and which engages against a complementary valve seat 21. A transverse wall 22 is located within the bottom portion 14^c and carries an upwardly extending shank portion 22^a. A spring 23 acts between the ball 20 and the transverse wall 22 for urging the ball 20 against the valve seat 21. This spring 23 has its top end coil bearing against the ball 20 and its bottom end coils encircling the shank portion 22^a of the transverse wall 22. It is proposed that the topmost coil of the spring 23 be securely attached to the ball for preventing the same from being disengaged therefrom when the blow off valve is urged into its open position.

The bottom end of the bottom portion 14^c of the passage 14 is closed by means of a plug 24 which carries a tubular stem 25. This tubular stem 25 has one of its ends connected with the interior of the bottom portion 14^c of the passage 14 and its free end projected to the center of the bristles 11 for causing the soap discharging therefrom to be applied directly to the center of the bristles. The self-feeding shaving brush is further provided with a means for locking the plunger 15 in its inwardly depressed position and for increasing the resistance of the blow off valve to prevent the discharge of soap therefrom when the brush bristles 11 are being washed and the same is shaken for the purpose of removing excess water therefrom. This means comprises a rotative stem 26 arranged at right angles to the bottom portion 14^c of the passage 14. The inner end of the stem 26 carries a cam 27 which engages the bottom end of the transverse wall 22. The transverse wall 22 is slidably mounted within the bottom portion 14^c of the passage 14 and in a certain turned position of the stem 26 the cam 27 urges the transverse wall 22 upwards to increase the tension of the spring 23 to more tightly seat the ball 20 upon its valve seat 21.

The stem 26 further carries a means for locking the plunger 15 in its inwardly urged position for closing the bottom end of the top offset portion 14^a of the passage 14. This means comprises a bolt 28 mounted upon an intermediate portion of the shaft 26 and located within a recess 10^b formed in the brush body 10. The plunger 15 is provided with complementary cutout 29 which is aligned with bolt 28 in its inwardly urged position permitting the bolt 28 to enter this cutout when the shaft 26 is turned and so hold the plunger against again being urged outwards by the spring 16 until the shaft 26 is rotated to disengage the bolt 28 from the cutout 29.

The top of the recess 10^b is closed by means of a portion of the material 10^c cut from the brush body for forming the recess 10^b. This portion of the brush body acts as a plug for sealing the top end of the recess 10^b. The outer end of the shaft 26 is provided with a knob 30 provided with a serrated periphery adapted to be manually grasped for facilitating the turning thereof. The shaft 26 at its outer end further carries an indicating pointer 31 registering upon a scale 32 formed upon the outside face of the brush body 10. This scale 32 is characterized by the letters C indicating "closed," and the letter O indicating "open."

The transverse wall 22 is provided with a plurality of passages 33 extended parallel therethrough for the purpose of permitting a free pas-

sage of soap therethrough in spite of the fact that the transverse wall 22 extends completely across the bottom portion 14^c of the passage 14.

The operation of this invention is as follows: 5 The cover 13 is removed and the chamber 12 of the brush body is filled with shaving soap. The plunger 15 is depressed for closing the bottom end of the offset portion 14^a of the passage 14 and for forcing soap located within the main central portion 14^b into the bottom portion 14^c to pass through the tubular stem 25 to the bristles 11. When the plunger 15 is urged inwards, soap passing from the main central portion 14^b will blow the valve 20 off its valve seat 21 permitting the soap to pass therethrough. When the plunger 15 is released, the spring 16 will urge the plunger into its outwardly extended position and the plunger 15 is adapted to be compressed as many times as desired for the purpose of supplying the desired quantity of soap to the bristles 11.

After completion of the shaving operation, and when it is desired to wash the bristles 11, the plunger 15 is urged inwards and the knob 30 rotated for turning the shank 26 into a position in which its indicating pointer 31 will be aligned with the letter C of the scale 32. This will cause the cam 27 to urge the transverse wall 22 upwards increasing the tension of the spring 23 to 20 more tightly seat the valve 20 upon its valve seat 21. This rotation will also pivot the bolt 28 causing the same to enter the cutout 29 and maintain the plunger in its new position against the action of the spring 16. The bristles 11 may 25 then be washed and shaken for removing the excess water therefrom without the danger of the shaving soap passing through the passage 14 and nullifying the washing operation.

While I have illustrated and described the preferred embodiments of my invention, it is to be understood that I do not limit myself to the precise constructions herein disclosed and the right is reserved to all changes and modifications coming within the scope of the invention as defined 45 in the appended claims.

Having thus described my invention, what I claim as new, and desire to secure by United States Letters Patent is:

50 1. A device of the class described comprising a body, a chamber and a passage connecting said chamber with the exterior of said body, a plunger transversely mounted in said body at right angles through said passage and extending from one side and when in an inward position cutting off passage through said passage, resilient means for urging said plunger outwards, a spring controlled blow off valve closing said passage at a point beneath said plunger, a stem rotative in said body and extending from one side, a cam on said stem 55 beneath said valve for increasing the resistance of said blow off valve when said stem is turned, and a bolt on said stem engageable with a cutout in said plunger when said plunger is pushed inwards and said stem is turned for locking the plunger in a retracted position.

60 2. A device of the class described comprising a body, a chamber and a passage connecting said chamber with the exterior of said body, a plunger transversely mounted in said body at right angles through said passage and extending from one side and when in an inward position cutting off passage through said passage, resilient means for urging said plunger outwards, a spring controlled blow off valve closing said passage at a point 65 beneath said plunger, a stem rotative in said 70 body and extending from one side, a cam on said stem beneath said valve for increasing the resistance of said blow off valve when said stem is turned, and a bolt on said stem engageable with a cutout in said plunger when said plunger is pushed inwards and said stem is turned for locking the plunger in a retracted position.

75 3. A device of the class described comprising a body, a chamber and a passage connecting said chamber with the exterior of said body, a plunger transversely mounted in said body at right angles through said passage and extending from one side and when in an inward position cutting off passage through said passage, resilient means for urging said plunger outwards, a spring controlled blow off valve closing said passage at a point beneath said plunger, a stem rotative in said

body and extending from one side, a cam on said stem beneath said valve for increasing the resistance of said blow off valve when said stem is turned, and a bolt on said stem engageable with a cutout in said plunger when said plunger is pushed inwards and said stem is turned for locking the plunger in a retracted position, said passage being characterized by a top offset end portion continuing into a main central portion in turn continuing into a bottom portion.

3. A device of the class described comprising a body, a chamber and a passage connecting said chamber with the exterior of said body, a plunger transversely mounted in said body at right angles through said passage and extending from one side and when in an inward position cutting off passage through said passage, resilient means for urging said plunger outwards, a spring controlled blow off valve closing said passage at a point beneath said plunger, a stem rotative in said body and extending from one side, a cam on said stem beneath said valve for increasing the resistance of said blow off valve when said stem is turned, and a bolt on said stem engageable with a cutout in said plunger when said plunger is pushed inwards and said stem is turned for locking the plunger in a retracted position, said passage being characterized by a top offset end portion continuing into a main central portion in turn continuing into a bottom portion, said main central portion being laterally extended completely through said brush body and housing said plunger.

4. A device of the class described comprising a body, a chamber, and a passage connecting said chamber with the exterior of said body, a plunger transversely mounted in said body at right angles through said passage and extending from one side and when in an inward position cutting off passage through said passage, resilient means for urging said plunger outwards, a spring controlled blow off valve closing said passage at a point beneath said plunger, a stem rotative in said body and extending from one side, a cam on said stem beneath said valve for increasing the resistance of said blow off valve when said stem is turned, and a bolt on said stem engageable with a cutout in said plunger when said plunger is pushed inwards and said stem is turned for locking the plunger in a retracted position, said passage being characterized by an eccentric top end portion continuing into a main laterally extending central portion in turn continuing into a concentric bottom portion, said main central portion being laterally extended completely through said brush body and housing said plunger, and means for maintaining said plunger in position within said main central portion and for holding said plunger against turning.

5. A device of the class described comprising a body, a chamber, and a passage connecting said chamber with the exterior of said body, a plunger transversely mounted in said body at right angles through said passage and extending from one side and when in an inward position cutting off passage through said passage, resilient means for urging said plunger outwards, a spring controlled blow off valve closing said passage at a point beneath said plunger, a stem rotative in said body and extending from one side, a cam on said stem beneath said valve for increasing the resistance of said blow off valve when said stem is turned, and a bolt on said stem engageable with a cutout in said plunger when said plunger is pushed inwards and said stem is turned for lock-

ing the plunger in a retracted position, said passage being characterized by an eccentric top end portion continuing into a main laterally extending central portion in turn continuing into a concentric bottom portion, said plunger being formed with a forwardly projected tail portion for closing the bottom end of the top offset end portion of the passage when said plunger is urged inwards.

6. A device of the class described comprising a body, a chamber, and a passage connecting said chamber with the exterior of said body, a plunger transversely mounted in said body at right angles through said passage and extending from one side and when in an inward position cutting off passage through said passage, resilient means for urging said plunger outwards, a spring controlled blow off valve closing said passage at a point beneath said plunger, a stem rotative in said body and extending from one side, a cam on said stem beneath said valve for increasing the resistance of said blow off valve when said stem is turned, and a bolt on said stem engageable with a cutout in said plunger when said plunger is pushed inwards and said stem is turned for locking the plunger in a retracted position, said passage being characterized by an eccentric top end portion continuing into a main laterally extending central portion in turn continuing into a concentric bottom portion, said blow off valve being located within the bottom portion of said passage.

7. A device of the class described comprising a body, a chamber, and a passage connecting said chamber with the exterior of said body, a plunger transversely mounted in said body and extending from one side and when in an inward position cutting off passage through said passage, resilient means for urging said plunger outwards, a spring controlled blow off valve closing said passage at a point beneath said plunger, a stem rotative in said body and extending from one side, a cam on said stem for increasing the resistance of said blow off valve, and a bolt on said stem for locking the plunger in a retracted position, said passage being characterized by an eccentric top end portion continuing into a main laterally extending central portion in turn continuing into a concentric bottom portion, said blow off valve being located within the bottom portion of said passage,

50 said blow off valve comprising a ball engageable upon a valve seat, a slidably mounted transverse wall bearing against said cam, and a spring operating between said ball and wall for urging said ball upon said valve seat.

8. A device of the class described comprising a body, a chamber, and a passage connecting said chamber with the exterior of said body, a plunger transversely mounted in said body and extending from one side and when in an inward position cutting off passage through said passage, resilient means for urging said plunger outwards, a spring controlled blow off valve closing said passage at a point beneath said plunger, a stem rotative in said body and extending from one side, a cam on said stem for increasing the resistance of said blow off valve, and a bolt on said stem for locking the plunger in a retracted position, said passage being characterized by an eccentric top end portion continuing into a main laterally extending central portion in turn continuing into a concentric bottom portion, said blow off valve being located within the bottom portion of said passage, said blow off valve comprising a ball engageable upon a valve seat, a slidably mounted transverse wall bearing against said cam, and a spring op-

erating between said ball and wall for urging said ball upon said valve seat, said cam being adapted to urge said transverse wall upwards and so increase the tension of said spring.

9. A device of the class described comprising a body, a chamber, and a passage connecting said chamber with the exterior of said body, a plunger transversely mounted in said body and extending from one side and when in an inward position cutting off passage through said passage, resilient means for urging said plunger outwards, a spring controlled blow off valve closing said passage at a point beneath said plunger, a stem rotative in said body and extending from one side, a cam on said stem for increasing the resistance of said 15

blow off valve, and a bolt on said stem for locking the plunger in a retracted position, said passage being characterized by an eccentric top end portion continuing into a main laterally extending central portion in turn continuing into a concentric bottom portion, said blow off valve being located within the bottom portion of said passage, said blow off valve comprising a ball engageable upon a valve seat, a slidably mounted transverse wall bearing against said cam, and a spring operating between said ball and wall for urging said ball upon said valve seat, said transverse wall being provided with passages extending therethrough for permitting soap to pass thereby.

ARTHUR TAUBE, JR.
